(57) **CLAIM**

The ornamental design for a solar powered red dot optic as shown and described.

DESCRIPTION

FIG. 1 is an isometric right side view of a first embodiment of a solar powered red dot optic;

FIG. 2 is an isometric left side view thereof;

FIG. 3 is top view thereof;

FIG. 4 is a bottom view thereof;

FIG. 5 is a front view thereof;

FIG. 6 is a rear view thereof;

FIG. 7 is a right view thereof;

FIG. 8 is a left view thereof;

FIG. 9 is an isometric right view of a second embodiment of a solar powered red dot optic;

FIG. 10 is an isometric left view thereof;

FIG. 11 is top view thereof;

FIG. 12 is a bottom view thereof;

FIG. 13 is a front view thereof;

FIG. 14 is a rear view thereof;

FIG. 15 is a right view thereof;

FIG. 16 is a left view thereof;

FIG. 17 is an isometric right side view of a third embodiment of a solar powered red dot optic;

FIG. 18 is an isometric left side view thereof;

FIG. 19 is top view thereof;

FIG. 20 is a bottom view thereof;

FIG. 21 is a front view thereof;

FIG. 22 is a rear view thereof;

FIG. 23 is a right view thereof;

FIG. 24 is a left view thereof;

FIG. 25 is an isometric right view of a fourth embodiment of a solar powered red dot optic;

FIG. 26 is an isometric left view thereof;

FIG. 27 is top view thereof;

FIG. 28 is a bottom view thereof;

FIG. 29 is a front view thereof;

FIG. 30 is a rear view thereof;

FIG. 31 is a right view thereof; and,

FIG. 32 is a left view thereof.

The broken lines in the drawings disclose unclaimed subject matter only and form no part of the claimed design.
